(57) **CLAIM**

The ornamental design for a “revolving storage rack for scissors,” as shown and described.

DESCRIPTION

FIG. 1 is a top front perspective view of a “revolving storage rack for scissors” showing my new design;

FIG. 2 is a front elevational view thereof;

FIG. 3 is a top plan view thereof;

FIG. 4 is a bottom plan view thereof; and,

FIG. 5 is a view similar to FIG. 1 showing the manner in which the “revolving storage rack for scissors” is utilized. The material shown in phantom in FIG. 5 is for environment only and does not form a part of the design.
